UNITED STATES PATENT OFFICE.

JAMES S. FREER, OF RUTHERFORD, NEW JERSEY.

ETCHING APPARATUS.

1,016,487.

Specification of Letters Patent.

Patented Feb. 6, 1912.

Application filed September 22, 1910. Serial No. 583,165.

To all whom it may concern:

Be it known that I, JAMES S. FREER, a citizen of the United States, residing at Rutherford, county of Bergen, and State of New Jersey, have invented a new and Improved Etching Apparatus, of which the following is a specification.

This invention relates to a novel apparatus for etching plates, the working surfaces of which are prepared in suitable or known manner, so as to leave those portions thereof, which are to be etched, exposed to the attack of the etching fluid.

By my invention, the surface of the plate is completely submerged during the etching process, and the bath is so agitated by means of submerged compressed air jets that the bath will effectively attack the plate. As during the etching process the working surface of the plate faces downward, no objectionable deposits can form thereon.

In the accompanying drawing: Figure 1 is a plan of an etching apparatus embodying my invention, and Fig. 2 is a vertical longitudinal section thereof.

A tank or receptacle 10 made of acid proof material, and containing the etching bath 11, is provided beneath the surface of said bath with a pair of alined bearings 12. These bearings accommodate the gudgeons 13 of a removable normally submerged shaft 14, adapted to be rocked by a hand lever 15 and located at a distance above the bottom of the tank. Shaft 14 is provided with a longitudinal groove 16 adapted to receive the lower end of the plate 17 to be etched, said plate being secured to the shaft by means of a suitable holder 18 or otherwise. Holder 18 is hooked over the top of plate 17 and is clamped to shaft 14, by means of a nut 19 engaging a threaded pin 20 of shaft 14. A pair of stops 21, 22 adapted to be engaged by lever 15, serve to sustain the plate either in a horizontal or a substantially upright position, the correlation of the parts being such, that when the plate is sustained in a horizontal position, its then lower surface, which is the surface to be etched, is completely submerged in bath 11 and is held at a distance above the bottom of tub 10, so that such lower surface is subjected to the action of the acid bath.

Below shaft 14, and at a short distance above the bottom of tank 10, there is suitably

supported a submerged air distributer 23 shown to consist of a pipe coil having a plurality of air egress openings 24 preferably on its lower side. Air distributer 23 communicates at one end by means of a suitable flexible coupling 25 with a compressed air tank, pump or other compressed air supply 26. By means of air distributer 23 a large number of minute air jets are projected into the etching bath, so that the latter is thoroughly agitated and aerated. This agitated and aerated bath will thus effectively attack the submerged working surface of plate 17, such surface being in a most complete and effective manner presented to the corroding action of the bath.

The operation will be readily understood. Plate 17 is fitted into seat 16 of shaft 14, and clamped to the latter by holder 18. Lever 15 is swung forward until it engages stop 21, in which position the working surface of the plate will assume a substantially horizontal position and be submerged in bath 11. Compressed air being admitted to coil 23, the bath will be aerated and agitated in the manner described to uniformly etch plate 17. During the etching operation, shaft 14 may be rocked from time to time by hand lever 15, so as to uncover plate 17, and permit the same to be inspected. When the operation is completed, shaft 14 is turned until lever 15 rests against stop 22, holder 18 is uncoupled from shaft 14, and the etched plate is unseated and lifted out of the bath.

It will be seen that by my invention, a thorough contact of the plate with the agitated body of the etching fluid will take place. Furthermore as the working surface of the plate faces downward, no objectionable deposits can form thereon, and finally no clogging up of the air ejecting orifices is liable to occur, owing to the fact that such orifices are formed along the bottom of the air distributer.

I claim:

1. An etching apparatus comprising a tank adapted to contain an etching bath, an air distributing pipe arranged at the bottom thereof and having a plurality of air egress openings, a pair of alined bearings in the tank above said pipe, a rock shaft hung in said bearings, means for clamping a work plate to said shaft, manually operable means for turning the shaft and thereby

swinging the work plate into a horizontal position beneath the level of the bath, and a stop for checking the descent of said plate.

2. An etching apparatus comprising a tank adapted to contain an etching bath, an air distributing pipe arranged at the bottom thereof and having a plurality of air egress openings, a pair of alined bearings in the tank above said pipe, a rock shaft hung in said bearings, a holder clamped to the rock shaft and having a hook shaped end that is adapted to engage a work plate, manually operable means for turning the shaft and thereby swinging the work plate into a horizontal position beneath the level of the bath, and a stop for checking the descent of said plate.

3. An etching apparatus comprising a tank adapted to contain an etching bath, an air distributing pipe arranged at the bottom thereof and having a plurality of air egress openings, a pair of alined bearings in the tank above said pipe and below the bath level, a rock shaft hung in said bearings, means for clamping a work plate to said shaft, a hand lever on the shaft, and a pair of stops adapted to be engaged by the lever and to thereby sustain the work plate either in a horizontal or a substantially upright position.

JAMES S. FREER.
